R. H. MacINNES
INSULATION BLOCK AND ELECTRICAL CONSTRUCTION FOR THE
TERMINALS OF ELECTRIC RANGES
Filed May 24, 1923

FIG 4

FIG 3

INVENTOR
ROBERT H. MACINNES
BY *R. H. MacInnes*
ATTY.

UNITED STATES PATENT OFFICE.

ROBERT H. MACINNES, OF HAMILTON, ONTARIO, CANADA, ASSIGNOR TO D. MOORE COMPANY, LIMITED, OF HAMILTON, ONTARIO, CANADA.

INSULATION BLOCK AND ELECTRICAL CONSTRUCTION FOR THE TERMINALS OF ELECTRIC RANGES.

Application filed May 24, 1923. Serial No. 641,265.

To all whom it may concern:

Be it known that ROBERT H. MACINNES, a subject of the King of Great Britain, residing at Hamilton, in the county of Wentworth and Province of Ontario, Canada, has invented certain new and useful Improvements in an Insulation Block and Electrical Construction for the Terminals of Electric Ranges, of which the following is a specification.

My invention relates to improvements in insulation blocks and electrical constructions for the terminals of electric ranges, and more particularly to the connections of the heating coils or resistance wiring to the lead wires connecting with the source of electricity, and consists essentially of an insulation block extending inwardly to the electric burner from the outside of the oven and provided with a plurality of holes through which extend the ends of the resistance wires to the outside, and a terminal insulation plate secured to the outside of the oven and provided with terminals to which are attached the ends of the resistance wires and the ends of the leads, said terminal plate being provided with a slot and bushing extending through the outer oven wall and through which the leads are carried to the intervening space between the inner and outer oven walls.

The object of the invention is to provide a device of the class specified which will afford the maximum accessibility and facilities for repairs to the terminals.

A further object is to provide such a device which will be simple, durable, efficient and inexpensive to manufacture.

A still further object is to provide means for carrying the lead wires through the space between the outer and inner oven walls and at the same time exposing the terminals thereof for repair.

These, together with other objects, may be attained by the construction, combination and arrangement of the parts as will be hereinafter more fully described, illustrated in the accompanying drawing, and pointed out in the claims hereunto appended.

Referring to the drawing:

Figure 1 is a top sectional view of a portion of the oven showing the insulation block and a portion of the terminal plate;

Figure 2 is a sectional side elevation of a

portion of the oven showing the insulation block and terminal plate also in section;

Figure 3 is a front elevation of a portion of the oven showing the terminal plate and insulation block;

Figure 4 is a front elevation of a portion of the oven showing the terminal cover plate; and,

Figure 5 is an enlarged sectional side elevation of the insulation block and terminal plate.

Similar reference characters refer to similar parts throughout the several views.

The oven is constituted, as usual, of double walls A and double floor B, with an intervening space between the walls which is packed with mineral wool, asbestos or other heat insulating material adapted to confine the heat within the oven.

The inner or upper part of the floor B is suitably recessed to form a well B' within which is contained the electric burner C consisting of a porcelain plate, for example, in grooves in which are woven the resistance wires or heating coils 4 suitable for three different temperatures of heat.

A block D consisting of porcelain, for example, is provided, which in itself is not new in construction. This block which is provided with an enlarged rectangular head D' is horizontally located between a portion of the flooring of the oven adjacent the burner C and extending through the walls of the oven to the exterior thereof.

To the exterior of the outer oven wall A is secured a terminal insulation plate E of porcelain, for example, provided with terminal recesses 5 in which are secured preferably metallic plates 6 by means of the bolts 7. These plates 6 extend upwardly in the recesses 5 and are tapped to receive terminal bolts 8. On the inner side of the lower end part of the terminal plate E is formed a longitudinal bushing 9 through which is provided a slot 10. This bushing extends through a corresponding slot in the outer oven wall and insulates the edges thereof.

The lead wires 11 are conveyed between the outer and inner oven walls A and pass to the interior thereof through the slot 10 in the terminal plate E thence upwardly to the terminal bolts 8, their ends being formed into terminals and secured to the said bolts.

The resistance wires 4 are conveyed

through holes 12 in the insulation block D, their ends being formed into terminals and secured to the terminal bolts 8 to meet the lead wires 11.

- 5 A suitable terminal cover plate may be provided, and by way of example I have illustrated a sheet metal detachable cover F which may be secured to the oven wall by the provision of lugs 13 adapted to engage 10 lips 14 formed in the wall A, and the opposite side of the cover may be secured by a swivel fastener 15.

There has thus been provided a simple and efficient device of the class described and 15 for the purpose specified.

Having now fully described my invention what I claim and desire to secure by Letters Patent, is:—

1. In a device of the class described, the 20 combination with an electric oven including walls, and resistance wires mounted within the oven, of a block of insulating material extending through one wall of the oven from the outside to the inside and having a 25 plurality of holes extending therethrough, a terminal plate of insulating material secured to the outside of said wall adjacent said block and having a slot therein, terminal fasteners secured to said plate, the free 30 ends of said resistance wires passing through the holes in said block and secured to said terminal fasteners, a bushing formed around the slot in said terminal plate on the inner side thereof and extending 35 through the oven wall to the inside, and lead wires passed through said slot and secured at their free ends to said terminal fasteners.

2. In a device of the class described, the 40 combination with an electrical oven includ-

ing double walls filled with heat insulating material and resistance wires mounted within the oven, of a block of insulating material extending through one double wall of the oven from the outside to the inside and 45 having a plurality of holes extending therethrough, a plate of insulating material secured to the outside of the outer wall adjacent said block and having a slot therein, terminal fasteners secured to said plate, the 50 free ends of said resistance wires passing through the holes in said block and secured to said terminal fasteners, a bushing formed around the slot in said terminal plate on the inner side thereof and extending 55 through the outer wall of the oven, and lead wires carried between the double walls, passed through said slot, and secured at their free ends to said terminal fasteners.

3. In a device of the class described, the 60 combination with an electric oven including walls, and resistance wires mounted within the oven, of a block of insulating material extending through one wall of the oven from the outside to the inside and having a 65 plurality of holes extending therethrough, a terminal plate of insulating material secured to the outside of said wall adjacent said block, terminal fasteners secured to said plate, the free ends of said resistance 70 wires passing through the holes in said block and secured to said terminal fasteners, and lead wires secured at their free ends to said terminal fasteners.

In testimony whereof I have affixed my 75 signature.

ROBERT H. MACINNES.
